UNITED STATES PATENT OFFICE.

ERNEST H. FOSTER, OF DUNGAN HILLS, NEW YORK, ASSIGNOR TO POWER SPECIALTY COMPANY, OF NEW YORK, N. Y., A CORPORATION OF NEW YORK.

SUPERHEATER FOR STEAM-BOILERS.

1,272,248.

Specification of Letters Patent. Patented July 9, 1918.

Application filed February 17, 1916. Serial No. 78,800.

To all whom it may concern:

Be it known that I, ERNEST H. FOSTER, a citizen of the United States, residing at Dongan Hills, Richmond county, and State 5 of New York, have invented certain new and useful Improvements in Superheaters for Steam-Boilers, of which the following is a full, clear, and exact description.

The invention for which I hereby present 10 specification and claims in connection with this application for Letters Patent resides in a superheater for that special type of steam boiler known as a return tubular boiler.

15 In such boilers the hot gases from the fire pass longitudinally under the shell of the boiler from front to rear and thence up through a combustion chamber and forward through the tubes of the boiler on their way 20 to the flue. To equip such a boiler with a superheater I have found it very desirable from the standpoint of economy and other reasons which will more fully hereinafter appear, to devise a special form of super- 25 heater, to support the same in an entirely new way, and to employ in connection therewith certain devices which, so far as I am aware, have not heretofore been used in such systems. Generally stated my improve- 30 ments are as follows:

The superheater is contained within the combustion chamber at the rear of the boiler proper. It consists, in part, of vertical tubes supported at their upper ends above the 35 chamber and outside of the same, and which enter the said chamber through covers which may either be fixed to the walls of the chamber and permit the supporting superheater tubes to move through them as the latter ex- 40 pand or contract, or which may be carried by and attached to said tubes so as to move bodily as such expansion or contraction takes place. At the lower ends the super- 45 heating tubes connect with headers which are spanned by a plurality of inverted U- 50 tubes, and drainage tubes are taken off from such headers through suitable openings provided for them in the walls of the furnace setting.

55 As the hot gases in this improved arrangement enter the bottom of the combustion chamber they pass up over the superheater and as some portion of such gases have not, up to this point, come in actual contact with the boiler heating surface, a high and uni-

form superheat is obtained with a minimum amount of superheater surface.

The supporting tubes which enter the combustion chamber constitute themselves a part of the superheating surface and the construction and mode of installing the entire device affords ready and easy access to the superheater while in use and greatly facilitates its removal in case of necessity.

In the annexed drawings I have illustrated the specific construction of a boiler of the above described type and of my improved superheater so far as it is necessary to convey to those skilled in the art a full understanding of the nature and purpose of the invention.

Figure 1 is a part sectional and side view of the rear of a boiler showing the improved superheater applied thereto. The section on which this figure is taken is illustrated by 75 the line $x-x$ of Fig. 2.

Fig. 2 is part section and rear elevation of the device of Fig. 1 on the line $y-y$ of that figure.

Fig. 3 is a top plane view of the parts 80 shown in Fig. 1, and

Fig. 4 is a section view, looking down on the line $z-z$ of Fig. 2.

A is a return tubular boiler under which is the usual passage for hot gases B, communicating through the opening C with the combustion chamber D at the rear. Above 85 this chamber there are placed I-beams E to afford a support for the superheater.

The latter is placed within the combustion chamber and comprises the vertical tubes F, F, not connected, one parallel pair at each end of the chamber, the upper ends of which are secured to and supported by the beams E by flanges or heads or in any 90 suitable manner. The forward pair of tubes F are connected by pipes G with the steam dome of the boiler, and the rear pair by pipes H with the throttle or its equivalent in the usual manner.

The lower ends of tubes F connect with and support headers I, which, in turn are spanned by and carry a plurality of inverted U-tubes J. Drainage tubes M lead from the headers out through the furnace wall.

The tubes F and J all of which constitute portions of the heating surface of the superheater are shown as covered with rings or corrugations of cast iron, resembling in this respect the superheaters habitually made 110

under a former patent granted to me, and now well known articles of commerce. The rings on the vertical supporting tubes F extend up to the covers L, which are metal plates covered with any suitable refractory material, preferably loosely fitting the openings at the sides of the combustion chamber through which the tubes F enter.

The covers rest upon flanges or the top of 10 the rings K surrounding the tubes F and move freely upon and down as the said pipes expand or contract under varying temperature. In this way I obtain a freely supported superheater which has no direct connection with the boiler, but which is free to 15 expand or contract, and which may be bodily removed without difficulty, should occasion arise for such removal.

For boilers of this type this superheater 20 is most efficient and useful. A high and substantially uniform heat is secured with a superheater of relatively small size, and in case of need, all parts of the same are easily accessible and removable.

25 What I claim is:

1. A superheater for horizontal return tubular boilers, located in the combustion chamber at the rear of the boiler, comprising in combination with tubes forming part of 30 the heating surface of the superheater secured at their upper ends outside the chamber, means for permitting said tubes to expand and contract where they pass through the arch of the combustion chamber, and 35 headers and superheater tubes supported by the lower ends of said tubes.

2. A boiler setting provided with a combustion chamber in the rear end having openings in the arch thereof, in combination with a superheater proper located in 40 said chamber in the direct path of a portion of the furnace gases, and means for suspending said superheater proper in said chamber comprising inlet and outlet tubes for the superheater projecting through said 45 arch openings and supported outside said heating chamber, and closures between the walls of the openings and the supporting tubes free to move in and out as the tube expands and contracts under the influence of 50 the heat.

3. A superheater for horizontal return tubular boilers located in the combustion chamber at the rear of the boiler, comprising inlet and outlet headers located within 55 said chamber, superheating elements spanning said headers and located in the direct path of the furnace gases, inlet and outlet tubes connected to said headers for freely supporting the same and for conveying the 60 saturated steam to and superheated steam from said headers, said inlet and outlet tubes passing through openings in the top of the boiler setting, and covers for said openings through which said tubes pass into said 65 chamber, said covers adapted to move upwardly and downwardly in said openings with said tubes as the latter contract and expand.

In testimony whereof I hereunto affix my 70 signature.

ERNEST H. FOSTER.
